US00D952652S

(12) **United States Design Patent** (10) Patent No.: **US D952,652 S**
(45) Date of Patent: **** May 24, 2022**

(54) **DISPLAY SCREEN OR PORTION THEREOF
WITH GRAPHICAL USER INTERFACE**

(71) Applicant: **KNOTCH, INC.**, New York, NY (US)

(72) Inventors: **Anda Gansca**, New York, NY (US);
Stephanie Voltsun, San Francisco, CA (US);
Rebecca Chaika, San Francisco, CA (US);
Aron Tzimas, New York, NY (US);
Yassine Abouhazim, New York, NY (US)

(73) Assignee: **KNOTCH, INC.**, New York, NY (US)

(**) Term: **15 Years**

(21) Appl. No.: **29/745,364**

(22) Filed: **Aug. 5, 2020**

Related U.S. Application Data

(63) Continuation of application No. 29/660,331, filed on Aug. 28, 2018, now Pat. No. Des. 895,641, which is a continuation of application No. 29/570,521, filed on Jul. 8, 2016, now Pat. No. Des. 829,226, which is a continuation of application No. 29/496,607, filed on Jul. 15, 2014, now Pat. No. Des. 764,507, which is a continuation-in-part of application No. 14/166,644, filed on Jan. 28, 2014, now abandoned.

CLAIM

The ornamental design for a display screen or portion thereof with graphical user interface, as shown and described.

DESCRIPTION

The patent or application file contains at least one drawing executed in color. Copies of this patent with color drawing(s) will be provided by the Office upon request and payment of the necessary fee.

The sole FIGURE is a front view of a display screen or portion thereof with a graphical user interface showing our new design.

The features shown in dash-dot lines the FIGURE are for illustrating environmental structure and form no part of the claimed design.
